US00D342061S

United States Patent [19]

Ogura et al.

[11] Patent Number: Des. 342,061

[45] Date of Patent: ** Dec. 7, 1993

[54] MAGNETIC OPTICAL DISK DRIVE

[75] Inventors: **Manabu Ogura; Kazuhito Sakota, both of Amagasaki; Yasushi Noda, Tokyo; Masayuki Suzuki, Tokyo; Keiji Uehara, Tokyo; Yoshiki Kirinoe, Tokyo, all of Japan**

[73] Assignees: **Mitsubishi Electric Corporation; Teac Corporation, Tokyo, Japan**

[*] Notice: The portion of the term of this patent subsequent to Nov. 23, 2010 has been disclaimed.

[**] Term: **14 Years**

[21] Appl. No.: **665,748**

[22] Filed: **Mar. 6, 1991**

[57]**CLAIM**

The ornamental design for a magnetic optical disk drive, as shown and described.

DESCRIPTION

FIG. 1 is a reduced perspective view of a magnetic optical disk drive showing our new design;

FIG. 2 is a front view thereof;

FIG. 3 is a right side view thereof the left side being identical in appearance;

FIG. 4 is a rear view thereof; and,

FIG. 5 is a top view thereof.

FIG. 1

FIG. 2

FIG. 3

FIG. 4

FIG. 5
